INVENTOR:

F. WESTERBECK,

BY Knight Tool Co., Inc.

UNITED STATES PATENT OFFICE.

FREDERICK WESTERBECK, OF ST. LOUIS, MISSOURI.

CONTAINER.

1,381,148.

Specification of Letters Patent. Patented June 14, 1921.

Application filed September 25, 1916. Serial No. 121,999.

To all whom it may concern:

Be it known that I, FREDERICK WESTERBECK, a citizen of the United States of America, a resident of the city of St. Louis, 5 State of Missouri, have invented certain new and useful Improvements in Containers, of which the following is a full, clear, and exact description, reference being had to the accompanying drawing, forming a part of this 10 specification.

My invention relates to a sheet metal container intended more particularly for use in holding ether or other commodities which must necessarily be kept in hermetically 15 sealed vessels, but which are of such flammable nature as to render it dangerous to close the filling openings by the use of solder which must be applied in a hot condition. By my improvement I close the filling opening 20 of a sheet metal container in a manner to render the container absolutely air tight, and accomplish this result by a sealing device requiring pressure only to render it effective, thereby avoiding the necessity for 25 the use of solder.

A further object of my invention is to provide a container of this kind which cannot be refilled or reclosed without the fact of the refilling and reclosing being apparent.

30 Figure I is a top view of my container.

Fig. II is an elevation of the container.

Fig. III is in part an elevation of the 35 upper end of the container and in part an enlarged vertical section through the neck and its closure.

Fig. IV is an enlarged top view of the neck of the container.

Fig. V is an enlarged cross section through the sealing member.

40 Fig. VI is an enlarged fragmentary vertical section illustrating the condition of the container neck and its closure after the seal has been broken, and the application of a stopper to close the neck following the 45 breaking of the seal.

In the drawings, 1 designates the body of my sheet metal container, and 2 is a filling and pouring neck which may be secured in any suitable manner to the body 1. The 50 neck 2 is provided at its upper end with an outwardly extending flange 3 which completely surrounds the upper end of the neck and carries a downwardly extending annular lip 4 concentric with the neck 2. The 55 annular lip 4 is provided with an external screw thread. The neck 2 and lip 4 provide

concentric inner and outer walls at the upper margin of the container, and these walls are united by the flange 3 which may be termed a top wall. 60

5 designates a cap having an annular flange which is internally screw threaded for application to the screw threaded lip 4 of the container neck. This cap is provided with a central aperture of a size equal to or 65 greater than the size of the opening at the upper end of the neck 2, and the top portion of the cap between said opening and the flange of the cap is adapted to overlie the horizontal flange 3 of the neck 2. Said top 70 portion of the cap is of such form that its inner face lies parallel with the top face of the horizontal flange 3 when the cap is applied to the container neck, and the opposing surfaces of said cap and horizontal 75 flange are grooved and ribbed so that a rib on one of these members will oppose a groove in the other member. Each member is preferably formed with a series of ribs and intervening grooves, and these ribs and 80 grooves upon and in each of the members are circular and concentric with each other. The ribs and grooves are seen most clearly in Fig. VI, and the ribs and grooves upon and in the flange 3 are designated respectively 85 3^a and 3^b, while the ribs and grooves upon and in the top of the cap 5 are designated respectively 5^a and 5^b.

6 designates a sealing disk which is of a size to fit within the cap 5 when the latter is 90 applied to the neck of the container. It is provided with a raised central portion which extends through the aperture in said cap, as seen in Fig. III. This sealing disk may be of any suitable, pliable or ductile 95 material but is preferably formed of tin or lead.

When the herein described closure is to be applied to the neck of my container, the flange of the cap 5 extends in a straight line 100 from the top of the cap, and, therefore, when the sealing disk 6 has been seated on the neck 2 so as to overlie the closure therein and extend onto the horizontal top flange 3 of the container neck, the cap may be readily 105 screwed onto the lip 4 extending downwardly from said horizontal top flange. In thus applying the cap it is screwed onto the container neck with a sufficient degree of pressure to cause the circular ribs on the 110 opposing elements 3 and 5 to force portions of the sealing disk into the circular grooves

in the opposite member. The sealing disk is thereby firmly wedged and compressed between alternating circular ribs and circular grooves with the result of producing an absolutely air tight seal around the upper end of the container neck and between said neck and the closure applied thereto.

To open my container it is only necessary to cut the sealing disk 6 adjacent to the wall 10 of the aperture in the cap 5 in a continuous course around this wall and by so doing a clear opening through the cap and into the neck of the container is produced. This cutting of the sealing disk is readily accomplished due to the nature of the material of which the disk is formed, and also due to the raised central portion of said disk. After the seal has been broken by cutting out its central portion in the manner mentioned, a 20 cork or other stopper may be readily introduced through the cap and into the neck of the container as illustrated in Fig. VI. To facilitate the seating of the stopper and its retention in the container neck, said neck 25 is preferably tapered as shown, and the diameter of the central aperture in the cap 5 is greater than the internal diameter of the neck.

To provide against refilling of my container with the closure in a condition similar to its original condition, I make the cap 5 of a material which may be readily bent and form its flange which fits the lip 4 of the container neck of a length sufficient to permit of said flange being bent or crimped into a position beneath said lip. The flange of the cap extends downwardly beyond the lower edge of the lip of the container neck, as indicated in dotted lines Fig. III, following the application of the cap to the container neck, and such projecting portion may be readily bent inwardly into the position shown by full lines Figs. III and VI. When the flange of the cap has been so bent, 45 it would be extremely difficult to rebend the flange of the cap, and consequently is practically impossible to remove the cap and the seal held thereby and reapply the closure without leaving it in such condition as to 50 indicate the removal and replacement.

I claim:—

1. A container comprising a sheet metal neck having an outwardly jutting horizontal top flange and an annular externally screw threaded lip extending downwardly from said top flange, an apertured cap comprising an annular top flange overlying the hori-

zontal top flange of said neck and an internally screw threaded flange fitted to said externally screw threaded lip, and a soft metal sealing disk closing the aperture in said cap and seated between the horizontal top flange of said neck and the top flange of said cap, one of said top flanges having a circular groove therein and the other top flange having a circular projection for forcing a portion of said soft metal sealing disk into said groove.

2. A container comprising a sheet metal neck having an outwardly jutting horizontal top flange and an annular externally screw threaded lip extending downwardly from said top flange, an apertured cap comprising an annular top flange overlying the horizontal top flange of said neck and an internally screw threaded flange fitted to said externally screw threaded lip, and a soft metal sealing disk closing the aperture in said cap and seated between the horizontal top flange of said neck and the top flange of said cap, one of said top flanges having a circular groove therein and the other top flange having a circular projection for forcing a portion of said soft metal sealing disk into said groove, the lower margin of said internally threaded flange being turned under the lower edge of said externally threaded lip so as to permanently lock said apertured cap to said neck, and said soft metal sealing disk being exposed to receive a cutting tool at the aperture in said cap.

3. A container comprising a sheet metal neck having an inner wall adapted to receive a stopper, an outer wall separated from said inner wall and provided with external screw threads and a top wall uniting said inner and outer walls, an annular cap comprising an annular top flange forming a circular aperture and an internally screw threaded flange extending downwardly from said annular top flange, said top flange overlying said top wall and said screw threaded flange being fitted to the external threads of said outer wall, and a soft metal sealing disk closing the aperture in said annular cap and having its marginal portion upset between said annular top flange and said top wall, said soft metal sealing disk being exposed to receive a cutting tool at the aperture in said cap, and the diameter of said aperture being greater than the internal diameter of the inner wall of said sheet metal neck.

FREDERICK WESTERBECK.
